UNITED STATES PATENT OFFICE.

FALTEN EIGE, OF TORONTO, CANADA, ASSIGNOR TO C. A. DUNHAM COMPANY, OF MARSHALLTOWN, IOWA, A CORPORATION OF IOWA.

RETURN TRAP.

Application filed June 25, 1923. Serial No. 647,659.

My invention relates to return traps of the class adapted for carrying water into a receptacle containing steam or other fluid under pressure, and it is particularly designed 5 for returning the water of condensation from the radiators to the boiler of a heating system.

It is the principal object of my invention to provide a new and improved form and 10 arrangement of parts, comprising a plurality of weighted levers adapted to cooperate to give a sharp sudden blow of some little power upon the valves by which the entrance and escape of steam and air are 15 controlled for regulating the operation of the device, whereby the mechanism may preferably be capable of opening the main steam valve against the pressure of the steam without the necessity for providing a 20 preliminary valve or other similar construction involving balanced or partially balanced steam pressure.

It is one of the specific objects of my invention to provide an arrangement of this 25 general type in which one weighted lever in its movement by gravity under the control of a float picks up a second weighted lever and carries it into position to move by gravity, the arrangement being such that the two 30 levers are permitted to have a limited swing in unison free of the valves and are brought into operative relation with the valves at the end of such free swinging movement.

It is another object of my invention to improve devices of this general type in sundry details hereinafter pointed out. The preferred means by which I have accomplished my several objects are illustrated in the accompanying drawings and are hereinafter specifically described.

That which I believe to be new and desire to cover by Letters Patent is set forth in the claims.

In the drawings—

45 Fig. 1 is a side view of my improved trap.

Fig. 2 is a vertical cross-section taken substantially at line 2—2 of Fig. 1, but with the weighted levers swung to their vertical 50 position for better showing the construction.

Fig. 3 is an enlarged detail view, being a section taken at line 3—3 of Fig. 2, with the parts in their intermediate position.

55 Fig. 4 is a longitudinal sectional view,

being taken substantially on line 4—4 of Fig. 2, but showing the parts in the position corresponding to that of Fig. 1.

Fig. 5 is an enlarged detail view, being substantially a section taken on line 5—5 of Fig. 2, but showing the steam valve open and the air valve closed.

Fig. 6 is a fragmentary view similar to Fig. 4, but showing the primary weighted lever in its uppermost position ready for a 65 downward movement by gravity.

Fig. 7 is a view similar to Fig. 6, but showing the primary weighted lever in position ready to take up and carry with it the secondary weighted lever. 70

Fig. 8 is a view similar to Fig. 7, but showing the secondary weighted lever in position to begin its downward stroke by gravity in unison with the primary weighted lever. 75

Fig. 9 is a view similar to Fig. 8, but showing the weighted levers again in operative engagement with the float arm in the position in which such levers are held by the air valve at the end of their operative 80 stroke after the opening of the steam valve.

Referring now to the several figures of the drawings, in which corresponding parts are indicated by the same reference characters, 85 15 indicates a closed casing of any suitable type, being preferably in the form of a casting, with an inspection plate 16 secured thereon at one end. A pipe 17, as indicated by dotted lines in Fig. 1, is connected at its lower end with the casing 15, for conducting 90 to the casing the water of condensation from the radiators of a heating system. As will be readily understood the casing is located preferably at a point above the level of the water in the boiler of the heating 95 system, the arrangement being such that when a connection is effected between the casing and the boiler with the steam pressure equalized above and below the body of water in the casing, such water will run by gravity from the casing into the boiler.

In the construction shown the casing 15 is connected with the boiler (not shown) by means of a pipe 18, which is shown equipped with a check valve 19. At one side 100 the casing 15 is provided with an auxiliary housing 20 secured thereon over an opening 21 by means of machine screws. As is best shown in Fig. 5, the housing 20 is provided with a socket 22 at one side, into 105 110

which is tapped a steam pipe 23 leading from the boiler. At the opposite side the housing 20 is provided with a socket 24 into which is tapped an air pipe 25.

5 Coming now to the system of weighted levers for operating the valves as herein-after described, 26 indicates a stud shaft having a driving fit in a boss 27 carried by the wall of the casing 15 at the side 10 opposite to that at which the housing 20 is located. Between the inner end of the stud 26 and a boss 28 formed on the outer wall of the housing 20, I have provided a shaft 29 which has revolubly mounted upon 15 one end portion thereof a collar 30 which is provided with a notch 31 in its inner end for receiving a pin 32 extending radially from the shaft 29, as is best shown in Fig. 3. As will be readily understood, by the 20 provision of the pin and slot the collar 30 is free to have a limited rotary movement with respect to the shaft 29. As is best shown in Fig. 5, the collar 30 is provided with a transverse groove 33 at one side for 25 the reception of the shanks 34 and 35 of valves 36 and 37 adapted to seat respectively in the air nozzle and the steam nozzle of the housing 20 above described. The ends of the shanks 34 and 35 are pivotally 30 connected with the collar 30 by means of a pin 38, the arrangement being such that the collar 30 serves as a crank for the operation of the valves 36 and 37. As will be readily understood, the rotation of the 35 collar 30 in clockwise direction in Fig. 5 is limited by the seating of the valve 36 and the rotation of the collar 30 in counter-clockwise direction in said figure is limited by the seating of the valve 37. It is thus 40 seen that the collar 30 has a very limited rotation, and it will be understood that the rotation of the shaft 29 is only slightly greater, being limited by the amount of rotation of the collar 30 plus that permitted 45 by the small amount of play between the pin 32 and the notch 31.

For operating the shaft 29 for opening and closing the valves 36 and 37, I have provided a lever 39 fixedly mounted upon 50 the shaft 29, so as to rock therewith, this lever comprising in the construction shown two arms connected together by a web 40. Between the upper ends of the arms of the lever 39 I have pivotally mounted a weight 55 41 by means of pins 42, the arrangement being such that the weight is free to swing between the arms of the lever. The lever 39 is shown at the limit of its swinging motion towards the right in Fig. 4, being 60 held in that position by the engagement of the valve 36 with its seat. The arrangement is such that when the lever 39 has swung an equal distance toward the left in Fig. 4 beyond the vertical position, the lever 65 will be at the limit of its motion toward

left in such figure, being held in such position by the engagement of the valve 37 with its seat. Limiting pins 39^a are also provided.

Upon the stud 26, a short distance from the lever 39, I have revolubly mounted a lever 43, this lever also comprising two arms joined together by a web 44. Between the upper ends of the arms of the lever 43 I have pivotally mounted a weight 45 which is held in position by means of pins 46. Upon opposite sides of the arms of the lever 43 upon each face of weight 45, I have provided lugs 47 adapted by contact with the arms of the lever to limit the swinging of the weight 45, as shown in Fig. 4. Lost motion connections are provided between the levers 39 and 43 by the use of a pin 48 carried by the lever 43 and extending between pins or lugs 49 carried by the lever 39. In the position shown in Fig. 4, the lever 43 is standing at the limit of its motion towards the right in said figure, being limited by the action of the pin 48 and the lugs 49 carried by the lever 39, which in turn is at the limit of its motion towards the right in said figure. The arrangement is such that the lever 43 is capable of moving an equal distance to the left beyond the vertical line, as shown in Fig. 4, in which suggested position the lever 43 would be limited by the contact of the pin 48 with the other one of the two lugs 49 carried by the lever 39.

Between the levers 39 and 43, I have revolubly mounted a float arm 50 carrying upon its lower end a float 51 of any suitable type. The collar 52 by which the float arm 50 is revolubly mounted upon the stud 26 is provided at one side with a lug 53 in which is fixedly mounted a pin 54 which extends into a circumferential slot 55 formed in the lever 43, as is best shown in Fig. 4. The play or lost motion thus provided between the lever 43 and the float arm 50 is substantially equal to one-half of the complete swing of the lever 43. It will thus be seen that when the float arm 50 moves the lever 43 upwardly into vertical position so as to cause the lever to pass the vertical position sufficiently to move further in the same direction by gravity, the lever 43 is permitted to swing to the limit of its motion in that direction independently of the float arm 50 and the float 51, by reason of the lost motion between the pin 54 and the slot 55.

In Figs. 1 and 4 of the drawings, the parts are shown in the position in which they stand when the casing 15 has been emptied. The pressure of the steam at the left of the check valve 19 in Fig. 1 holds the valve closed. With the float 51 at its lowermost position, and with the larger or primary weight 45 and the smaller or secondary weight 41 at the limit of their motion toward

- the right in Fig. 4, the steam valve 37 will be standing closed and the air valve 36 will be standing open so as to permit the escape of air from the casing 15. The water of 5 condensation from the radiators is accordingly permitted to gather in the casing 15, air in the casing 15 being displaced through the air pipe 25 past the valve 36. As the 10 level of the water rises in the casing 15, the float 51 will also rise, swinging towards the right in Fig. 4, serving to move the lever 43 towards the left in said figure. When the water in the casing 15 reaches its uppermost desired level, the lever 43 will have 15 reached its vertical position as shown in Fig. 6, ready for its free downward swing by gravity towards the left in Fig. 4. When the lever 43 has swung to a position very slightly at the left of the vertical plane 20 through the axis of the shaft 26, as is shown in Fig. 7, the pin 48 carried by the lever 43 will come into contact with the lug 49 of the lever 39 at the left of the lever 39 as shown in said Fig. 7, serving to move the lever 39 25 towards the left in unison with the lever 43. When in the continued movement of the levers toward the left in Fig. 7, the lever 39 reaches its vertical position, as is illustrated in Fig. 8, the two levers will be in readiness 30 for their free swinging movement toward the left in that figure, both of said levers being then actuated by gravity independently of each other. When the two levers have moved in unison by gravity in this fashion 35 a short distance, the pin 32 carried by the shaft 29 will come into contact with the end of the notch 31 of the crank collar 30, serving to apply the momentum of both of the weighted levers toward the left in Fig. 9, 40 which is the same as toward the right in Fig. 5, serving to open the steam valve against the pressure of the steam in the pipe 23, and serving at the same time to close the valve 36. By reason of the application of the momentum of the two weighted levers to the 45 valve by a sharp, sudden blow, the valve 37 is opened by a very much smaller weight or aggregate of weights, than could be done if the mass of the weights alone were relied upon. The arrangement of the parts is such that the opening of the steam valve 37 and the closing of the air valve 36 are completed when the levers 39 and 43 reach the limit of their movement toward the left in Fig. 9, 50 in which position the pin 54 is again in engagement with one of the ends of the slot 55 of the lever 43.
- As will be readily understood, upon the opening of the steam valve 37 and the entrance of the steam into the casing 15, the water is permitted to escape from the casing 15 past the valve 19 through the pipe 18 into the boiler. As the level of the water is lowered in the casing 15, the float arm 50 55 will, of course, swing downwardly towards
- the right in Fig. 1, serving to carry the lever 43 past the vertical position, the lever 43 in turn serving to carry the lever 39 past the vertical position, and the two levers then swinging together, each by gravity independently of the other, so as to bring the force of the two weighted levers to bear upon the valves 36 and 37 at the end of the stroke of such levers for again closing the steam valve 37 and opening the air valve 36. 70
- While I prefer to employ the construction as illustrated in the drawings and as above described, it will be understood that I do not desire to be limited to the precise details of the construction shown, except as the same 75 is specifically claimed, inasmuch as it is evident that many changes may be made in the construction without departing from the spirit of my invention.
- I claim:
1. A return trap comprising a closed casing including a valve housing at one side of said casing, inlet and outlet connections in the casing for water of condensation, a fixed stud shaft projecting inwardly from one side wall of the casing, and a revolute shaft journaled at its respective ends in the free end of the stud and in the outer wall of the valve housing, valves mounted in the valve housing, a collar rotatably mounted on the shaft, operating connections between the collar and the valves, a pin and slot lost-motion connection between the shaft and collar, a weighted lever fixed to the shaft, a lever pivoted on the stud and having a float at its free end, and lost motion connections between the float lever and the weighted lever whereby the raising or lowering of the float will swing the weighted lever to one side or the other of a vertical position. 85
  2. A return trap comprising a closed casing including a valve housing at one side of said casing, inlet and outlet connections in the casing for water of condensation, a fixed stud shaft projecting inwardly from one side wall of the casing, and a revolute shaft journaled at its respective ends in the free end of the stud and in the outer wall of the valve housing, valves mounted in the valve housing, a collar rotatably mounted on the shaft, operating connections between the collar and the valves, a pin and slot lost-motion connection between the shaft and collar, a weighted lever fixed to the shaft, a second weighted lever freely pivoted on the stud, lost-motion connections between the two levers, a third lever also pivoted on the stud and having a float at its free end, and lost-motion connections between the float lever and the second weighted lever. 110
  3. A return trap comprising a closed casing including a valve housing at one side of said casing, inlet and outlet connections in the casing for water of condensation, a 115

- fixed stud shaft projecting inwardly from one side wall of the casing, and a revoluble shaft journaled at its respective ends in the free end of the stud and in the outer wall of the valve housing, valves mounted in the valve housing, a collar rotatably mounted on the shaft, operating connections between the collar and the valves, a pin and slot lost-motion connection between the shaft and collar, a weighted lever fixed to the shaft comprising a pair of upstanding parallel arms and a weight pivotally suspended between the upper ends of the arms, a lever pivoted on the stud and having a float at its free end, and lost motion connections between the float lever and the weighted lever whereby the raising or lowering of the float will swing the weighted lever to one side or the other of a vertical position.
4. A return trap comprising a closed casing including a valve housing at one side of said casing, inlet and outlet connections in the casing for water or condensation, a fixed stud shaft projecting inwardly from one side wall of the casing, and a revoluble shaft journaled at its respective ends in the free end of the stud and in the outer wall of the valve housing, valves mounted in the valve housing, a collar rotatably mounted on the shaft, operating connections between the collar and the valves, a pin and slot lost-motion connection between the shaft and collar, a weighted lever fixed to the shaft comprising a pair of upstanding parallel arms and a weight pivotally suspended between the upper ends of the arms, a second weighted lever freely pivoted on the stud, this lever also comprising a pair of upstanding arms and a weight pivotally suspended between the arms, lost-motion connections between the two levers, a third lever also pivoted on the stud and having a float at its free end, and lost-motion connections between the float-lever and the second weighted lever.
5. A return trap comprising a closed casing, an outlet connection to a boiler, a one-way valve therein, a valve housing projecting outwardly from one side of the casing and in open communication with the casing, a horizontal shaft mounted in this housing and projecting into the casing, an air outlet valve and a steam inlet valve each positioned substantially radially of the shaft in the valve housing, a pivot-pin mounted eccentrically on the shaft, a valve rod for each of the valves pivoted on this pin whereby a rocking movement of the shaft will open one valve and close the other, a weighted lever on the shaft within the casing adapted to operate the valves when swung to one side or the other of a vertical position, a float pivoted within the casing on the same axis as the shaft, and lost-motion connections between the float and the weighted lever.

centrically on the shaft, a valve rod for each of the valves pivoted on this pin whereby a rocking movement of the shaft will open one valve and close the other, a weighted lever on the shaft within the casing adapted to operate the valves when swung to one side or the other of a vertical position, a second weighted lever and a float each pivoted within the casing on the same axis as the shaft, and lost-motion connections between the float and the second mentioned lever, and between the two levers.

6. A return trap comprising a closed casing, an outlet connection to a boiler, a one-way valve therein, a valve housing projecting outwardly from one side of the casing and in open communication with the casing, a horizontal shaft mounted in this housing and projecting into the casing, an air outlet valve and a steam inlet valve each positioned substantially radially of the shaft in the valve housing, a pivot-pin mounted eccentrically on the shaft, a valve rod for each of the valves pivoted on this pin whereby a rocking movement of the shaft will open one valve and close the other, a weighted lever on the shaft within the casing adapted to operate the valves when swung to one side or the other of a vertical position, a float pivoted within the casing on the same axis as the shaft, and lost motion operating connections between the float and the weighted lever.

7. A return trap comprising a closed casing, an outlet connection to a boiler, a one-way valve therein, a valve housing at one side of the casing, a horizontal shaft mounted in this housing and projecting into the casing, an air outlet valve and a steam inlet valve each positioned substantially radially of the shaft in the valve housing, a collar pivoted on the shaft, a lost-motion connection between the shaft and collar, a valve rod for each of the valves pivoted at one end in the collar eccentrically of the shaft whereby a rocking movement of the shaft will open one valve and close the other, a weighted lever on the shaft adapted to operate the valves when swung to one side or the other of a vertical position, a float pivoted within the casing, and lost motion operating connections between the float and the weighted lever.

FALTEN EIGE.
